UNITED STATES PATENT OFFICE

2,411,479

SHOE MANUFACTURE

Isidor Tarlow, Brockton, Mass.

Application September 18, 1944, Serial No. 554,664

2 Claims. (Cl. 12—142)

1. This invention relates to shoe manufacture

and pertains more particularly to improvements in comfort shoes and their method of manufacture. The principal purpose of the invention is to produce a shoe which will maintain its lasted shape, without the necessity of employing shoe trees or other devices to preserve the flat set of the sole, and which is unusually comfortable to the wearer, especially in the vamp area.

One of the primary features of the improved construction is the provision of a resilient, sheet-like bottom filler which is secured to the lasted insole under tension and continuously resists any tendency of the shoe sole to bow upwardly at the toe, thus holding the sole flat and avoiding the formation of wrinkles in the insole or creases in the vamp.

Another feature is the incorporation in the vamp of a cushion-like, resilient layer or lining which not only affords general comfort to the wearer by relieving excessive pressure on corns or bunions, but also resists distortion of the vamp and, when combined with the resilient bottom filler, tends to counteract any excessive strain of the tensioned filler and thus assists in preserving the initial shape of the shoe sole as well as the forepart of its upper.

Recommended embodiments of the invention are illustrated in the accompanying drawings, but it will be understood that the structural details of the shoe parts herein shown and described may be widely varied without departing from the essence of this invention as defined in the appended claims.

In the drawings,

Fig. 1 is a bottom view of a lasted shoe prepared for the application of a preferred form of resilient bottom filler sheet;

Fig. 2 is a plan view of the sheet filler adapted to be applied to the insole of Fig. 1;

Fig. 3 is a transverse section across the forepart of a shoe equipped with the improved sheet filler of Fig. 2 and the vamp lining of Fig. 5;

Fig. 4 is a similar view illustrating an optional form of fastening between the insole and bottom filler;

Fig. 5 is a side view, partly in section, of a shoe equipped with the tensioned bottom filler and the improved vamp lining;

Fig. 6 is a fragmentary perspective view of one form of the vamp lining or insert; and

Fig. 7 is a similar view of an optional form of vamp lining.

The invention is herein shown as embodied in a man's welt shoe, but it will be evident that

2. the improved features may be incorporated in other types of shoe, if desired. It will also be understood that the improved shoe is lasted, soled and finished according to any customary manufacturing methods, except as the incorporation of the novel features above explained is herein-after described.

The sheet-like, resilient bottom filler 11 may consist of a suitably shaped piece of perforated scrap rubber of the character described in my Patent No. 2,053,502, dated September 8, 1936, and when such a filler is employed it possesses all the advantages explained in that patent as well as the novel features therein disclosed. Other stretchable, resilient, or contractile materials or compositions will, however, satisfy the purposes of the present invention, so long as they may be suitably fastened to the insole under appreciable tension and thereby cause the sole of the finished shoe to maintain its flat condition under normal use.

The resilient sheet is adapted to fill the forepart cavity of the usual welt insole 12 which, as shown in Fig. 1, has been lasted to the upper 13 and welt 14, on the last 15. In accordance with this invention longitudinally spaced fastening elements, such as the snap sockets 16 of Figs. 1 and 3, are attached to the insole 12 before it is tacked on the last. The shoe is then lasted, welted, and prepared for bottom filling.

The sheet filler 11 is prepared to fit the bottom cavity and complementary fastening elements, such as the snap studs 17 of Figs. 2 and 3, are secured thereto at longitudinally spaced intervals. The fasteners are provided at the toe and ball regions, and preferably also at the shank, as shown; but the third fastening will be omitted if the filler does not extend into the shank of the shoe.

40. The distance between any pair of fasteners on the resilient filler is substantially less than the distance between any complementary pair of fasteners on the insole. The differential may be approximately five-eighths of an inch in each case, as in the arrangement shown in Figs. 1 and 2.

Hence, in applying and securing the filler, the resilient sheet must be stretched longitudinally to attach the complementary snap fasteners, and 50. is then held in place under appreciable tension. Suitable cement is preferably applied between the meeting faces of the insole and filler to bind them together; and after the cement has dried, the outsole 18 is applied and secured according to common practice.

3

In the modification shown in Fig. 4, split rivets or staples 19 are employed as the fastening elements on the insole, the sheet filler having suitably spaced openings receiving the prongs of the rivets or staples, and constructing the complementary fastening elements of the filler when the latter is applied under tension to the lasted insole. The rivet head may, of course, be countersunk, if desired.

In Figs. 3 and 5, the vamp of the shoe is equipped with the improved cushion layer 21 inserted as an interlining between the upper 13 and the usual fabric lining 22 and secured therewith to the insole by the ordinary inseam stitch of a welt shoe. As shown in Fig. 6, this cushion layer preferably consists of a thin sheet of sponge rubber or other soft and resilient material, having small perforations 23 therethrough to permit adequate circulation of air. The pores and perforations of the layer 21 also tend to obviate damage to the upper resulting from perspiration, for perspiration will collect therein and be evaporated without wetting the upper proper 13.

Other suitably porous or permeable sheets may be satisfactorily employed as the cushion lining or layer, such as foam rubber, or wool felt; and a rubber layer 24 may be spread-coated or vulcanized on the outer side of the textile fabric lining 22, if desired, as indicated in the modified form of Fig. 7. When applied as a separate sheet, the cushion layer is preferably stretched outwardly from the center and cemented or otherwise attached to the upper 22 under tension, before the upper parts are assembled, and thereafter cemented to the lining 13 to unify the vamp at or prior to lasting of the shoe.

The yielding resilience of the cushion layer 21 or lining tends to relieve pressure on the foot and also, because it is connected through the insole to the resilient bottom filler, to assist the stretched filler 11 in maintaining the shape of the sole and upper at the forepart of the shoe, and to resist excessive tension of the stretched filler. The combined effect of the stretched filler sheet 11 of the sole and the stretched layer 21 of the vamp results in a balance of tension which maintains the sole in flat position and preserves the fitting qualities of the vamp, when the shoe is off the foot, yet permits flexing of the sole and maintains the upper parts in unwrinkled condition

4

when the shoe is worn. The usual leather upper and fabric lining are inherently stretchable, under the flexing caused by walking and will conform to the condition of the resilient cushion layer 21, so that said layer obviates wrinkling of the lining or the upper under all conditions.

A shoe constructed as herein described is extremely comfortable to wear and maintains its unwrinkled and uncreased shape indefinitely.

10 The springiness of the sole which is constantly urged toward a flattened condition, under the counteracting effect of the vamp lining, by the tension of the resilient filler sheet, is noticeable when the shoe is flexed in walking; and the flatness of the sole is apparent when the foot is relaxed as well, as when the shoe is removed from the foot.

I claim:

20 1. A method of making shoes comprising the steps of preparing an insole having fastening elements spaced longitudinally on its bottom surface, lasting an upper to the insole, preparing a sheet-like, stretchable and resilient bottom filler having complementary fastening elements spaced longitudinally thereof with the distance between each pair of complementary fastenings substantially shorter than the distance between the corresponding pair of fasteners on the insole, stretching the filler and fastening it to the insole under tension, and then applying an outsole.

25 2. A method of making shoes comprising the steps of preparing an insole having fastening elements spaced longitudinally on its bottom surface, preparing an upper by cementing to the vamp portion of the upper proper a layer of porous, stretchable and resilient material, while said layer is in a stretched condition, and then applying a lining to said layer, lasting the laminated upper to the insole while said layer is under tension, preparing a sheet-like, stretchable and resilient bottom filler having complementary fastening elements spaced longitudinally thereof with the distance between each pair of complementary fastenings substantially shorter than the distance between the corresponding pair of fasteners on the insole, stretching the filler and fastening it to the insole under tension, and then applying an outsole.

ISIDOR TARLOW.
